S. HAMILTON,
SELECTIVE CIRCUIT PUSH BUTTON SWITCH,
APPLICATION FILED MAR. 7, 1921.

1,437,891.

Patented Dec. 5, 1922.

UNITED STATES PATENT OFFICE.

SAMUEL HAMILTON, OF BARRINGTON, NOVA SCOTIA, CANADA.

SELECTIVE-CIRCUIT PUSH-BUTTON SWITCH.

Application filed March 7, 1921. Serial No. 450,503.

To all whom it may concern:

Be it known that I, SAMUEL HAMILTON, a subject of the King of Great Britain, residing at Barrington, in the Province of Nova Scotia and Dominion of Canada, have invented certain new and useful Improvements in Selective-Circuit Push-Button Switches, of which the following is a specification.

10 This invention relates to selective circuit switches for closing any one of a plurality of circuits from a common source.

The primary object of the invention is to provide a selective circuit switch adapted 15 for use in hotels, hospitals, factories, and department stores or the like, where it may be installed for the purpose of selectively signalling to any one of a number of departments.

20 A further object of the invention is the provision of a device of the above described character, in each circuit of which is installed an annunciator, and a signalling device.

25 A further object of the invention is a device of the above described character, which is simple in construction, compact in formation, and resembling in external appearance, the ordinary push button switch.

30 A further object of the invention is the provision of a device of the above described character, which has all of its operating parts enclosed by an oscillating cover, with the exception of suitable indicating means 35 located exteriorly thereof.

Other objects and advantages will be apparent during the course of the following detailed description.

In the accompanying drawings, forming 40 a part of this specification, and in which similar reference characters designate corresponding parts throughout the same:

Figure 1 is a plan view of the improved selective switch, showing the external appearance thereof.

Figure 2 is a cross sectional view showing the operating construction of the improved switch.

Figure 3 is a plan view partly diagrammatic, and showing certain internal construction of the improved selective switch.

Figure 4 is a fragmentary view showing certain details of construction.

In the drawings, wherein for the purpose 55 of illustration is shown the preferred embodiment of my invention, the letter A des-

ignates a stationary support, upon which is oscillatively mounted a support B. A cover C is detachably connected to the support B, and houses the switch structure D for selectively closing the contacts E of a plurality of circuits. Indicating means F, is positioned exteriorly of the selective switch push button structure, and cooperates with the switch means D and contacts E in closing a particular circuit.

The stationary support A is preferably circular in formation, and disc shaped, and provided in concentric alignment therewith and upon the rear thereof with a plurality of depressed openings 10, near the outer circumference, which are adapted to receive a plurality of contact pins 11. The contact pins 11 are provided with heads 12, seated in suitable depressions in the face 13 of the support A, and having their stems 14 projecting rearly through the apertures 10 and upon which are mounted the nuts 15 for adjustably securing the terminals 16 of various branch circuits. The heads 12 are so positioned in the face 13 of the support A that their outer surfaces lie flush and substantially in the same plane as that of the face 13. The support A is of wood or similar insulating material, and provided with the openings 18 adapted to receive screws or the like, to attaching the same to a wall or similar structure.

The oscillative support B is concentrically mounted upon the stationary support A by means of a spindle 20. The spindle 20 is provided with a shoulder 21 adapted to engage in a suitable aperture through the support B, and having a reduced screw threaded shank 22 projecting from the rear face of said support B and adapted for disposition within the screw threaded recess 23 in the face 13 of the stationary support A. The spindle 20 is provided upon the shoulder 21 with a suitable slot adapted for receiving a screw driver or the like to facilitate placing of the same on the support A; and is provided with a suitable screw threaded aperture centrally thereof adapted to detachably receive a screw 24 for positioning the terminal wire connection 25, in such manner that the screw 24 will act as a common contact, the function of which will be hereinafter more fully set forth. The wire 25 is led through suitable openings in the support A and spindle 20 to position the same beneath the head of the

screw 24. The oscillative support B is circular in formation, and of less diameter than the stationary support A.

The cover C, is altogether similar in appearance to the ordinary push button and is provided with a hollowed depression 30 adapted to receive the switch control means D. The cover C is provided with an outer circumferential flange 31 adapted to engage the axial circumference of the oscillative support B and to contact upon the face 13 at the outer circumference thereof substantially as shown in Figure 2 of the drawings. The cover C is detachably connected to the support B by suitable screws 33 or the like.

The switch control means G comprises the spring contact arm 35, which is substantially S-shaped in formation and attached to the inside of the cover C near the outer circumference thereof by means of a detachable screw 36. The contact arm 35 is, however, connected by the screw 36 intermediate its ends and has the upper end thereof projecting into a recess 37 notched upon the outer circumference of the support B, from which position the contact arm is sinuously bent to be disposed within a depression 39 upon the rear surface of the flange 31; and when the cover C is positioned upon the support B, the sinuously bent portion 38 is normally maintained under slight compression to lie in the line of contact with the heads 12 of contacts 11. Thus, as the cover C is rotated with respect to the stationary support A, the end 38 of the spring 35 will contact with the various heads 12 of contacts 11 in successive order. The opposite end 40 of the spring 35 is yieldably dependent, in such manner that a hooked end 41 thereof engages the push button 42, disposed within an aperture 43 centrally of the cover C. The push button 42 is similar in construction to the ordinary push button, with the exception that it is provided with a shoulder 44 disposed upon the inside face of the cover C and maintained to engage said cover C by the normal yieldable compression of the spring 35. In normal position, it can be seen from the foregoing, that the end 38 of the spring 35 normally is in contact with either of the heads 12 of contacts 11, while the end 40 of the spring 35 is held in yieldable spaced relation with respect to the common contact 24.

The indicating means F comprises the indicator arm 46, detachably mounted upon the external circumference of the stationary support A as by a screw 47. The forward part of the indicator 46 is pointed and downturned to overlie the outer surface of the detachable cover C. Upon the outer surface 48, which the arm 46 overlies, suitable delineations 49 are positioned having reference numerals or similar indicia thereon.

The delineations 49 of course, correspond to

the various contacts 11 and cooperate therewith, in the correct determination of a particular circuit.

Each one of the contacts 11 has a branch circuit wire 50 connected thereto, and has in circuit therewith an annunciator 51 and a signal 52. The respective wires 50 are grounded at 53, to a common conductor, which in a building is ordinarily a steam pipe, water pipe or the like. The common contact 24 is provided with the terminal 25 to which is connected the current wire 54 having in circuit therewith a battery, or electrical energy supply 55, said wire 54 being grounded at 56 to the common conductor which is in circuit with the wires 50.

Thus the improved selective signal switch is adapted for use in hospitals, hotels, department stores and the like, where the same may be positioned at a particular place, having the wires 50 lead to the different departments, whereby the particular department may be selectively called by means of bridging the particular contact 11 of that department and the common contact 24, by means of the arm 35.

Thus, if it is desired to call a particular department, the cover C is oscillated, until that particular department delineations 49 is positioned directly below the pointer 46, and upon pushing the button 42, the switch arm 35 will be depressed, in such way that the circuit will be completed in the system, and the annunciator 51 and the signal 52 will respectively be actuated to notify that particular department.

For installation of the device in a hospital, the various delineations 49 could correspond to the different departments of a hospital, such as number 1 of the delineations being a nurses' call, one of the lead wires 50 of which conveys the circuit to the annunciator 51 and signal 52 within the nurse's room. The number 2 of the delineations 49 could indicate a call for an interne, and a particular lead wire 50 could convey the current to an annunciator 51 and signal 52 within the interne's department. In the illustration as shown in Figure 1, the indicator 46 is pointing to the number 3 of the delineations 49, and which could be used to indicate a call for a doctor, the particular lead wire 50 leading to an annunciator 51 and signal 52 within the doctor's office. If the switch button 42 were to be depressed when the indicator 46 pointed to the delineation numbered 3, it would depress the contact arm 35 so that said contact arm 35 would bridge communication between the common contact 24 and the head 12 of middle one of the contact 11 as shown in Figure 3 of the drawings, thus establishing the circuit in the wire 50 leading to the doctor's annunciator 51 and signal 52. Similar calls can be sent to any of the vari-

ous departments as indicated by the delineations 49 by mere oscillation of the cover C in order that the pointer 26 will indicate the desired departments to be called.

5 Various changes in the shape, size and arrangement of parts may be made to the form of invention herewith described, without departing from the spirit of the invention or the scope of the subjoined claims.

10 I claim:

1. In a selective circuit push button switch, the combination of a stationary support, a plurality of contacts mounted upon said support, a cover, means for oscillatively connecting said cover to said support, a common contact, a spring normally in line to contact either of said first mentioned contacts, and a button mounted upon said cover adapted for manual operation to cause said 20 spring to contact with said common contact whereby selective connection will be established between said common contact and either of said first mentioned contacts.

2. In a selective circuit push button switch, the combination of a stationary support, a plurality of contacts mounted upon said support, a common contact, a cover, a revoluble cover support detachably mounted upon said stationary member, a push 30 button, a spring mounted upon said cover and normally having one end thereof in line of contact with said first mentioned contacts, said other end engaging said switch button whereby upon manual operation of said button, said spring will engage said common contact, and establish selective communication between the same and one of said first mentioned contacts.

3. In a selective circuit switch, the combination of a supporting member, a cover, means oscillatively connecting said supporting member and said cover, a plurality of contacts upon said supporting member, a

common contact thereon, a spring connected intermediate its ends to said cover, one end 45 of said spring normally under compression to be in line of contact with said first mentioned contacts, the other end of said spring yieldably held in spaced relation to said common contact, whereby upon depression 50 thereof said spring will establish communication with said common contact and either of said first mentioned contacts.

4. In a selective circuit switch, the combination of a stationary member, a plurality 55 of contacts thereon, a spindle detachably mounted in said stationary support, a cover, a cover support oscillatively mounting said cover upon said spindle, a common contact, and means carried within said 60 cover adapted to selectively bridge said common contact and either of said first mentioned contacts.

5. In a selective circuit switch, the combination of a stationary support, a plurality 65 of contacts arranged in arcuate alignment upon said support, a spindle detachably mounted upon said stationary support, a common contact carried by said spindle, and insulated from said first mentioned contacts, 70 a second support oscillatively mounted upon said spindle, a hollow cover detachably mounted upon said second support, and enclosing all of said contacts, a switch spring substantially S-shaped in formation detachably mounted within said cover, said spring having one end in normal line of contact 75 with said first mentioned contacts, and said other end yieldably spaced from said common contact, a push button adapted for 80 manual operation to depress said spring to contact the same with said common contact, and indicating means upon the exterior of said cover for selectively determining which of said contacts shall be bridged.

SAMUEL HAMILTON.
